(57) **CLAIM**

The ornamental design for a cartridge container for preservation of amplification reagents, as shown and described.

DESCRIPTION

This application is related to U.S. patent application Ser. No. 29,540,395, filed on Sep. 24, 2015, which claims priority to Japanese Design Application No. 2015-006433, filed Mar. 25, 2015, the entire disclosures of which are hereby incorporated herein by reference.

FIG. 1 is a perspective view of a cartridge container for preservation of amplification reagents showing my new design;

FIG. 2 is another perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a sectional view thereof taken along line 9-9 of FIG. 3; and,

FIG. 10 is a sectional view thereof taken along line 10-10 of FIG. 7.
